UNITED STATES PATENT OFFICE

2,546,203

AUTOMATIC OR MANUALLY ACTUATED
HYDRAULIC JACK

Woodrow G. Tucker, Stanfield, Oreg.

Application November 30, 1946, Serial No. 713,349

2 Claims. (Cl. 254—86)

1

This invention relates to improvements in pressure actuated lifting jacks of the hydraulic type.

One of the principal objects of the invention is the provision of a jack of this character which is readily adaptable to the axles of a vehicle and which may be used individually or in multiple to elevate one or more of the wheels of the vehicle from the ground by a simple valve mechanism located on the interior of the vehicle within convenient reach of the operator.

Another object is the provision of a device of this kind which is of compact, durable construction and which when collapsed into an inoperative position offers no air resistance or drag to the vehicle when in motion.

These and other objects will appear as my invention is more fully hereinafter described in the following specification, illustrated in the accompanying drawings and finally pointed out in the appended claims.

In the drawings:

Figure 1 is a front elevation of a jack made in accordance with my invention and with parts broken away and in section for convenience of illustration.

Figure 2 is a top plan view of Figure 1 with fragments also broken away.

Figure 3 is a view similar to Figure 1 showing the jack in an operative or lifting position.

Figure 4 is a front elevation of the device in movement between an inoperative and operative position.

Figure 5 is a diagrammatic layout of the source of pressure, pipe lines and control valve for directing pressure to points of application.

Referring now more particularly to the drawings.

In Figures 1 to 4, reference numeral 1 indicates a supporting bracket secured to the front and to the rear axles of a vehicle near their opposite ends by any suitable means, such as clamps or U bolts indicated at 2. Swingably mounted to the bracket 1 by means of a pin or bolt 3 is a connecting rod 4, to one end of which is secured a piston 5 which operates within a positioning cylinder 6. The head of the cylinder is formed into a hollow shaft 7 for rotatable attachment to the head 8 of a lifting cylinder 9 which is also swingably mounted to the bracket 1 by means of a hinge pin or bolt 10, extending outwardly therefrom. From the foregoing it will be seen that movement of the positioning cylinder 6 to the right, as viewed in Figures 2 and 3 will force the lifting cylinder 9 to move downwardly into a ver-

2

tical position as shown in Figure 3. Slidably mounted within the cylinder 9 is a lifting jack consisting of a piston 11 having a connecting rod 12 terminating in a spherical end 13 to which is attached for universal movement, a foot plate 14.

The shaft 7 is bored as at 15 and is in open communication at one of its ends, by means of a duct 16, with the interior of the cylinder 6 as shown. Fluid under pressure is directed to the 10 interior of the hollow shaft 7 by means of a tube or pipe 17 connected with a fluid pressure pump to be hereinafter more fully described. Between the ends of the bore in the shaft 7 I form a port 18 and in spaced relation to the port 18 form a slot 19 or vein 19. The head 8 of the cylinder 9 is formed with an intake duct 20 adapted for open communication through a check valve 21 with the port 18 in the hollow shaft when the cylinder 9 has been swung downwardly through 90 degrees 20 by means of the cylinder 6. An exhaust port 22 is also formed in the cylinder head 8 and is in communication with the vein 19 through a check valve 23.

When fluid pressure from the tube 17 enters 25 the bore 15 in the shaft 7 it is directed through the duct 16 against the piston 5 which, of course, forces the cylinder 6 to move outwardly or to the right as aforesaid. This movement forces the cylinder 9 to move downwardly into the position 30 shown in Figure 3, whereat the duct 20 comes into communication with the port 18, whereupon the fluid pressure is then applied to the piston 11 in the cylinder 9 to force the jack downwardly into contact with the ground or surface beneath 35 the vehicle. This causes a resultant upward movement of the cylinder 9 which through the medium of the bolt 10, bracket 1, and axle, elevates the wheel from the ground. Meanwhile, of course, the exhaust port or duct 22 is held closed 40 by the check valve 23 to prevent the pressure from backing up through the vein 19 into the hollow shaft 7. Both cylinders 6 and 9 are at all times filled with fluid and as their respective pistons move toward their ends the fluid in advance 45 of the piston flows through a duct 24 in the cylinder 9 into a return tube 25, and from the end of the cylinder 6 into a return tube 26. Both of said tubes terminate in open communication with any suitable form of T connection, or the 50 like, as indicated at 27 (see Figure 5) for returning the fluid through a single tube 28 to the control valve, generally indicated at 29 in Figure 5, and which consists of a housing 30 and a core 31 rotatable therein by means of an actuating handle 32. The valve may be of any approved type

for directing fluid pressure from any suitable pressure pump 33 through pressure pipe 17 to the interior of the hollow shaft 7, and by another setting for returning the fluid from the ducts 24 and 26, as aforesaid, from the cylinders 9 and 6, respectively, into a fluid supply tank 34 which by a return line 35 is connected with the intake side of the pump 33.

When the valve is moved into "down" position the weight of the vehicle causes the lifting cylinder to move downwardly with respect to the lifting jack. This of course forces the fluid previously applied to the piston 11 to exhaust through the duct 22 into the vein 19 throughout the entire upward swing of the cylinder 9 and into the hollow shaft 7, thence through the tube 17 and back into the supply tank 34. At this same time the flow of the fluid through the tubes 25 and 26 is reversed to replace the fluid back of the pistons in the cylinders 6 and 9.

The reverse flow of the fluid from the interior of both cylinders out through the tube 17 causes the cylinders to resume their retracted horizontal starting positions as illustrated in Figures 1 and 2.

The foot plate 14 is connected to the end of the connecting rod 12 for universal movement so that it will readily accommodate or adapt itself to any irregular ground surface or roadway it contacts for the lifting operation.

Although I have shown and described the invention as applied to vehicles it is to be understood that such use does not necessarily prescribe its limit of utility, since obviously the invention could be successfully applied to other operations requiring forces to be automatically and progressively applied in angular relation to each other.

While I have shown a particular form of embodiment of my invention, I am aware that many minor changes therein will readily suggest themselves to others skilled in the art without departing from the spirit and scope of the invention. Having thus described the invention, what I claim as new and desire to protect by Letters Patent is:

1. A lifting jack for vehicles comprising a positioning cylinder pivotally and slidably mounted

with respect to an axle of the vehicle, a lifting cylinder mounted with respect to said axle for movement into vertical and horizontal positions by pivotal attachment at one of its ends 5 to said positioning cylinder, a piston slidably mounted in the lifting cylinder, a shaft attached at one of its ends to the piston and its opposite end extending outwardly from the end of the lifting cylinder, valve means formed within the pivotal connection between said cylinders for progressively directing pressure into the positioning cylinder for moving said lifting cylinder from a horizontal to a vertical position and to the piston therein for forcing said shaft downwardly against a surface beneath the vehicle to force said lifting cylinder and said axle upwardly with respect to said surface.

2. A lifting jack for vehicle comprising a pair of cylinders pivotally attached to each other and 10 to an axle of the vehicle, valve means formed within the pivotal connection between the cylinders and operable by swinging movement of the cylinders with respect to each other for directing pressure to one of said cylinders for moving 15 it longitudinally with respect to the axle and through its pivotal connection with the other cylinder for moving the same into a vertical position with respect to the axle, and means movable within and extending outwardly from said last 20 mentioned cylinder for contacting the surface beneath the vehicle to resist said pressure to cause a resultant upward movement of said cylinder and the axle to which it is attached.

WOODROW G. TUCKER.
